UNITED STATES PATENT OFFICE

SAMUEL MILNE, OF EDINBURGH, SCOTLAND

DIGESTION OF RAW MATERIALS

Application filed March 16, 1928, Serial No. 262,265, and in Great Britain March 26, 1927.

This invention relates to processes involving chemical re-actions with the cell contents of natural organized materials and has for its object the control of the desired chemical 5 re-action with a suitable, applied re-agent.

The invention consists in the manufacture of products by chemical re-action between a suitable, applied re-agent and the cell contents of a natural organized material, (fibrous 10 or otherwise) wherein the re-action is controlled by the application thereto of an externally generated, relatively high frequency, transient, electro-motive force.

One application of the invention is in the 15 acceleration of the re-actions in the digestion of raw fibrous materials for paper making and like purposes.

The acceleration of the re-actions is observed in one or some of the following effects, 20 considerable shortening of the time, reduction in the quantity of the applied re-agent required for digestion, a very much more complete removal of the non-cellulose matter required to be eliminated, the rendering effective 25 of a re-agent ordinarily ineffective or relatively ineffective and the suppression of unwanted re-actions.

Various experiments have been made to obtain effective application of the necessary, 30 transient, electro-motive force for the acceleration of the re-actions in digestion, and the means employed for such application have produced various degrees of effect.

The accompanying drawings illustrate dia- 35 grammatically various electrical arrangements for the different experiments which will hereinafter be described, in which

Figs. 1, 2 and 2a illustrate the first series 40 of experiments.

Figs. 3, 4 and 5 illustrate a further series 45 of experiments employing induction.

In one experiment on a laboratory scale a small steel digester cylinder was used, holding about eight ounces of dry material, which 50 could be closed and in which the pressure and temperature conditions could be maintained approximating to the conditions in a full sized commercial digester. The digester was charged with five ounces of grass and thirty 55 ounces of liquor containing half-an-ounce of

caustic soda (commercial). The digester *a* see Fig. 1 was stood on a gas ring *b* and was grounded through a coil of wire *c* of about 25 turns. The time for the experiment was chosen when the local broadcasting wireless 55 station was transmitting. The gas was lighted and the digester heated to 280° F. and maintained at this temperature for 30 minutes. When cool the digester was opened and the pulp appeared to be exceptionally well 60 cooked. On washing it was found that the non-cellulose matter was completely removed, and the pulp was a noticeably light colour. When tested for bleaching it was found to bleach easily to a full white. 65

This experiment was repeated frequently with unvaryingly successful results.

Subsequently still further improvements were effected in the results by the use of other means for applying the transient, electro-motive force, which means employed the same source of power, namely electrical oscillations obtainable from wireless transmission, such means consisting in the use of an aerial *d* (see Fig. 2) and a series condenser *e*, by which the aerial circuit could be tuned, connected to the top of the digester *a*, the bottom of the digester being earthed, either directly or through a coil *f* (see Fig. 2a), the best results however being obtained with a coil in the earth 70 circuit. 75

The essential points which stand out in these experiments are the small values of the applied, transient, electro-motive force and the high frequency thereof. 80

The application of the methods employed in commercial processes presents several difficulties, in particular in obtaining the insulation of the digester for the inter-position of a coil in the earth circuit. This difficulty is not however insuperable as with high frequency currents the digester, though earthed, is relatively insulated by the impedance of the earth circuit and by its own capacity. Considering the digester and its connections as an oscillating circuit, its resistance and therefore its insulation, will be maximum when the applied, oscillating, electro-motive force 90 is in resonance therewith and therefore when 95 100

the induced electro-motive force is at its maximum.

In another series of experiments the digester was earthed as directly and completely as possible and a transient electro-motive force was applied to its contents by placing an insulated wire or an insulated metal plate *g* (see Fig. 3) around the digester, forming as it were a condenser element. This element was connected by a commutator *h* and brushes *j* and *k* to the positive and negative terminals *m* and *n* of a two volt accumulator in the case of which was inserted a cadmium plate *o* which was connected to earth. The commutator was rotated by an electric motor (not shown) to give contact with each terminal about 80 times a minute. The positive and negative terminals of the accumulator relative to the cadmium plate and therefore to earth, have a positive potential of 2.24 volts and 0.14 volts respectively, and therefore the positive charge on the plate *g* is changed 160 times a minute. With each change of charge on the condenser are produced damped oscillations which provide the necessary transient electro-motive force. This experiment was ultimately tested on a 5 ton digester with results which indicated considerable acceleration of the re-actions. Experiments are in progress to ascertain the relations (if any) between the size of the condenser, the voltage changes, the frequency of the voltage changes, the proportional quantity of the re-agent and time of the cook, and further to ascertain as far as possible the optimum conditions.

The experiments so far made indicate the desirability of a large area of condenser and small voltage changes and the possibility of a reduction of 33½ per cent. of the re-agent and 50% reduction of time.

In other experiments on the same lines an accumulator was used to provide the voltage for charging the condenser plate and the terminals of the accumulator were connected to give voltage changes from 4 volts to 2 volts (see Fig. 4) and from 6 volts to 4 volts (see Fig. 5), and for other values and with equally promising results. By this means the necessity for the use of the cadmium cell was avoided, and beneficially as this threatened to present trouble in maintenance.

A characteristic feature of each cook was that whereas ordinarily the pulp stood as a solid cone in the centre of the digester, it now always assumed a concave form spreading up the sides of the digester. Further, the operatives remarked on the ease of discharging and refilling of the digester as compared with the other and like digesters, also upon the ease of washing the pulp and the extreme regularity of the cook. The fine quality and colour of the pulp was also noticeable, as well as the ease with which it would bleach, the grass used being Esparto.

An important feature was that the charge on the condenser must never be negative or other and, (for the purpose of digestion), undesirable re-actions were stimulated, and that the maintenance of a positive charge was beneficial. Obviously there are other ways by which an electrician could arrange for the required charges and changes thereof. It was noticed that the use of a potentiometer however, to supply the respective voltages, was relatively a failure owing probably to the heavy damping of the charge and discharge and thereby again indicating that the control of the re-actions resulted from the high frequency transient, electro-motive force produced by the charge and discharge. In this connection also it will be noted that experiments with a low frequency alternator (about 30 cycles) to provide the voltage changes of the charge proved a failure, either with or without a positive bias, and undoubtedly due to the absence of high frequency, transient, electro-motive force.

The frequency of the voltage changes did not appear to materially affect the results, the important factor being the shock of charge and discharge producing high frequency oscillations, the frequency of which depended upon the natural frequency of the various circuits.

Results have been successfully obtained with the condenser placed within the digester, but insulation difficulties in maintenance will naturally be against such an application.

It is not possible at this stage to assign specific frequencies of oscillations for particular effects nor to state any limits for the intensity of potential which may be used.

It must be clearly understood that the control obtained by this invention is entirely distinct from any electrolytic action and further that electrolytic action is to be avoided as far as possible.

It has been observed that in the case of digestion with acids, where a positive potential is maintained on the condenser element, there is a noticeable preservation of the metal parts of the vessel, pipes, etc. from the normal action of the acid. This is a commercial advantage for which no specific claim is made.

What I claim is:—

1. The process, in the manufacture of products by chemical reaction between a suitable applied reagent and the cell contents of a natural organized material, for controlling the reaction, consisting in the application of an externally generated relatively high-frequency, transient, electromotive force.

2. The manufacture of products according to claim 1, characterized in that the mass of the reaction is electrically earthed and in that the controlling energy is applied by induction.

3. The manufacture of products according

to claim 1, characterized in that the mass of the reaction is electrically earthed and in that the controlling energy is applied inductively by means of an adjacent insulated condenser element to which the electro-motive force is applied from an oscillating electric circuit.

4. The process according to claim 1, further characterized by the application of an electrical bias-potential, as set forth.

5. The process of digestion of raw materials for the manufacture of paper, wherein the reaction is conducted in an iron digester, electrically connected to earth and wherein the digestive reactions are accelerated by the inductive effect of a relatively high-frequency transient electrical potential applied to an adjacent element, as set forth.

6. The process of digestion of raw materials according to claim 5, characterized by the application of a positive bias-potential to the said adjacent element, as set forth.

7. The process of digestion of raw materials according to claim 5, further characterized in that the said element comprises an electrically conductive insulated plate, as set forth.

8. In the manufacture of products by chemical reaction between a suitably applied reagent and the cell contents of a natural organized material, the application thereto of an externally generated relatively high-frequency transient electro-motive force by means of a tuned oscillating electric circuit, as set forth.

In testimony whereof I have signed my name to this specification.
